CHAIR BASE OR SIMILAR ARTICLE

Wayland B. Parker, South Boston, Va., assignor to Schlumberger Limited (Schlumberger N.V.), Houston, Tex., a corporation of the Netherlands Antilles

Filed Feb. 17, 1966, Ser. No. 1,085

Term of patent 14 years

(Cl. D15—1)

FIG. 1. is a front perspective view of a chair base or similar article embodying my design;

FIG. 2 is a bottom plan view of the base; and
FIG. 3 is a front elevational view of the base.

I claim:

The ornamental design for a chair base or similar article, substantially as shown.
